UNITED STATES PATENT OFFICE.

ENOCH HENRY EATON, OF MOULTON, IOWA, ASSIGNOR OF ONE-HALF TO
J. A. PAYNE, OF SAME PLACE.

ROTARY ENGINE.

SPECIFICATION forming part of Letters Patent No. 611,289, dated September 27, 1898.

Application filed August 3, 1897. Serial No. 646,869. (No model.)

To all whom it may concern:

Be it known that I, ENOCH HENRY EATON, a citizen of the United States of America, and a resident of Moulton, in the county of Appanoose and State of Iowa, have invented a new and useful Rotary Engine, of which the following is a specification.

The object of this invention is to provide improved means for utilizing the expansive force of steam for the propulsion of mechanism.

My invention consists in the construction, arrangement, and combination of elements hereinafter set forth, pointed out in my claim, and illustrated by the accompanying drawings, in which—

Figure 1 is a sectional elevation of my engine, longitudinally in the main shaft. Fig. 2 is a transverse sectional elevation on the line 1 1 of Fig. 1. Fig. 3 is an elevation of the cam-wheel detached from the engine.

In the construction of the engine as shown the numeral 10 designates the main shaft, mounted for rotation in bearings 11 12, formed in or fixed to the sides 13 14 of the engine-casing. The sides 13 14 of the casing are circular, and a rim 15 is mounted on the peripheries thereof and secured thereto. The inner or adjacent faces of the sides 13 14 of the casing are plane and equidistant at all points from each other, being parallel and of the same thickness. Mounted rigidly on the same shaft 10 is a piston-head 16 of cylindrical form and of less diameter than the inner diameter of the casing, thus forming an annular steam-chamber between the periphery of the piston and the axial face of the casing-rim 15, which steam-chamber is traversed radially of the main shaft by a wing or head 17, fixed to the piston 16 and projecting from the periphery thereof. The outer end of the wing or head 17 engages with and travels in contact on the axial face of the rim 15 of the casing.

The rim 15 of the casing is mounted on and fixed to a suitable base or support 18. The rim 15 is apertured at 19 in one portion, and a gate 20 is mounted for reciprocation in said aperture and in slide bearings or grooves 21 22, formed in the inner faces of the sides 13 14. A stem 23 is fixed to and extends from

the outer end of the gate 20 and is loosely connected at its outer end to the inner bifurcated end portion of a lever 24. The lever 24 is fulcrumed near its center on a pin 25, seated in ears 26 27, formed on a steam-chest 28, and the outer end of the lever is connected with a pitman 29. The pitman 29 is vertically positioned between guides 30 and 31, fixed to the side 13 of the casing, and a pin 32 is seated in and transversely of the lower end of said pitman. A head 33 is formed on the end of the pin 32, and an anti-friction-sleeve 34 is mounted loosely on said pin between the head 33 and the pitman 29.

A wheel or disk 35 is mounted rigidly on the main-shaft pin at some little distance from the side 13 of the casing, and said wheel is provided with a cam-groove 36 in the face thereof adjacent to said casing. The groove 36 is reamed out, cut under, or dovetailed in cross-section to receive and retain in its inner portion the head 33 on the pitman-pin. The groove 36 is annular throughout a major portion of its length and is depressed at one point abruptly toward the main point or axis of the wheel to form a reentrant portion 36^a, which is of greater width than the major portion of the groove to permit insertion and removal of the head 33.

On the opposite side of the steam-casing from the wheel 35 there is located an eccentric disk 37, connected by the usual strap 38 to a pitman 39, the eccentric disk being rigidly mounted on the main shaft 10. The upper end of the pitman 39 is connected to the extremity of the horizontal arm of the bell-crank lever 40, which bell-crank is fulcrumed on the steam-chest 28 and has the extremity of its vertical arm pivoted to the outer end of a valve-stem 41. A slide-valve 42 is mounted on the inner end of the stem 41 for reciprocation within the steam-chest and controls an ingress-port 43 to the steam-chamber in advance of the aperture 19 of the rim 15. Immediately at the rear of the aperture 19 in the rim 15 there is located an exhaust-port 44, always open to the atmosphere, through which the steam exhausts from the annular steam-chamber.

In the practical operation of this device steam is admitted to the chest 28 through the

supply-pipe 45, is governed in its admission to the cylinder by the slide-valve 42, enters the cylinder between the wing or head 17 and the gate or valve 20, and expanding therein forces the wing or head 17 in a rotary path around the interior of the rim 15, and since the head 17 is connected rigidly with the disk 16 and main shaft it follows that the travel of the head will cause the rotation of the shaft 10 and mechanism connected thereto. In the rotation of the shaft 10 the wheel 35 is rotated and the cam-groove therein operates the pitman 29 and lever 24 to raise and lower the valve-stem and valve 20 at such times in relation to the rotation of the disk 16 as is necessary to permit the passage of the wing or head 17 beyond the gate or valve 20. In the rotation of the shaft 15 the eccentric 37 is rotated and, acting through the strap 28, pitman 39, and bell-crank lever 40, reciprocates the slide-valve 42 and cuts the steam on or off, as is desirable, to control the admission of the steam at the proper time to the space in front of the valve 20 and at the rear of the wing or head 17.

I claim as my invention—

A rotary engine comprising the following elements in combination, to wit: a casing having ingress and egress ports; a concentric piston mounted within said casing; a

gate 20 mounted for reciprocation transversely of the casing; a lever mounted for oscillation; a stem connecting one end of the lever with the gate 20; a pitman connected to the other end of the lever; guides mounted on the casing and laterally extended therefrom to receive and guide the pitman; a pin laterally extended from the lower end of the pitman and provided with a beveled head 33; a main shaft carrying the concentric piston; a wheel mounted on the main shaft and provided with a cam-groove in its face adjacent to the casing, which cam-groove is reamed out and undercut to receive the beveled head 33 and widened at the reentrant portion thereof to permit removal and insertion of said head therein; a steam-chest mounted on the casing; a slide-valve in said steam-chest controlling the ingress-ports to the casing; a bell-crank lever mounted on the casing and connecting at one end to the slide-valve; an eccentric connected to the other end of the bell-crank lever; an eccentric wheel or disk mounted on the main shaft and connected with the eccentric; and a power-wheel mounted on the main shaft.

ENOCH HENRY EATON.
